UNITED STATES PATENT OFFICE.

JOHN SOMMER, OF PEORIA, ILLINOIS, ASSIGNOR TO KEYSTONE STEEL & WIRE COMPANY, OF SOUTH BARTONVILLE, PEORIA, ILLINOIS.

REEL.

1,372,784.

Specification of Letters Patent. Patented Mar. 29, 1921.

Application filed June 13, 1919. Serial No. 303,970.

To all whom it may concern:

Be it known that I, JOHN SOMMER, a citizen of the United States, residing at Peoria, in the county of Peoria and State 5 of Illinois, have invented new and useful Improvements in Reels, of which the following is a specification.

This invention has reference to reels, and relates particularly to that type of reel on 10 which is wound barbed-wire during the operation of manufacture and subsequently shipped to jobbers and dealers.

One object of the invention is to provide a reel of the character referred to, which 15 is made entirely of metal to displace the ordinary wooden reels which are expensive, and in most instances cannot be used more than once; whereas, a metallic reel has the advantage of being used over and over again 20 and thus decreasing the cost, which is an item of considerable moment in manufacture.

A further object of the invention is to so construct the reel that the process of electric-welding may be utilized in the manufacture thereof, thereupon cheapening the 25 production as well as affording a reel which will be strong and rigid.

I am aware that metallic reels, as a substitute for wooden reels, have been proposed, but I am not aware of a reel embodying the novel features herein disclosed. And while I have preferred to mention the 30 use of the reel for barbed-wire reeling, it is of course understood that it may also be used for reeling plain wire and other materials.

That the invention may be more fully understood, reference is had to the accompanying drawing forming a part of the specification, in which:—

Figure 1 is a front elevation of my improved reel, a part being broken away to better illustrate the same, and

Fig. 2 is an end elevation of the reel;

Figs. 3 and 4 show modified forms of the end construction of the reel, the modification being directed particularly to the members which form the webs.

Like characters of reference denote corresponding parts throughout the figures.

The reel comprises the two preferably rectangular shaped wire end members 1, 1. These end members are each preferably formed from a single piece of wire, of the 55 proper gage, so as to have the four corners 2, 2, 2, 2.

The meeting ends 3 of the formed end members where they meet being "butt" 60 welded, as shown.

The end members are connected by, preferably, four substantially U shaped wire bars or rods 4, which form the body of the reel on which the barbed-wire, or other material is wound. These bars or rods 65 4 have the straight parallel horizontal portions 5 and their opposite ends are bent at right angles and inclined slightly out of the perpendicular, as at 6, and where the bodies of the horizontal and angularly inclined 70 portions of the bars or rods 4 unite depressions 7, are formed for purposes to be explained. The angularly inclined end portions 6 of said bars or rods 4 intersect the corners 2 of the end members 1, and are 75 "lap" welded thereto, as shown.

The horizontal parallel portions 5 of the bars or rods 4 are connected, at their opposite ends by members 8, which are substantially star-shaped. These members are 80 formed from a single strand of wire bent to produce the radially arranged twisted bodies 9, producing the end loops or eyes 10 through which the bars or rods 4 are 85 passed and have a bearing, and the centrally or axially arranged opening 11 through which is inserted a spindle, not shown, which supports the reel when winding and unwinding the barbed-wire, wire or other material. The ends of the wire constituting the members 8 meet and are "butt" 90 welded, as at 12, as shown.

When manufacturing the article shown, it is preferable to weld the end of each bar or rod 4 to its respective corner 2 of an end 95 member 1, and then weld the opposite ends of said bars or rods 4 to the opposite end member 1. Before this operation is completed the loops or eyes 10 of the members 8 are slipped over the bars or rods 4, leaving 100 said members on the bars or rods 4 between their ends, but without being seated in the

depressions 7. After the welding operation, at the points 2, which tends to separate the bodies 5 of said bars or rods 4 a distance slightly more than the distance 5 between the centers of the diametrically opposed loops or eyes 10, the loops or eyes then are slid along the bodies 5 until they seat themselves in the depressions 7 which locks the members in position on said 10 bars or rods 4 as will be understood, lending stability to the whole structure and providing webs to receive the supporting spindle.

In the modified forms of the device shown 15 in Figs. 3 and 4, the end members 1^a are preferably circular in form instead of being rectangularly shaped as shown in Fig. 1, and said end members 1^a are "butt" welded, as shown. The end members 1^a are connected by the U-shaped wire bars or rods 4 which do not differ from the construction shown in Fig. 1, and in the modified forms the ends of said wire bars or rods 4 are "butt" welded to the end portions, as shown.

25 In Fig. 3, the webs for the reel comprise the wire members 13 which are bent to form the circular central portions, 13^a and are formed with the oppositely radially extended portions 13^b terminating in the loops or 30 eyes 13^c, which receive the wire bars or rods 4. It will be observed that there are duplicate wire members 13 at each end of the reel, one wire connecting diametrically opposed wire bars or rods 4 and the other member 35 connecting the other diametrically opposed wire bars or rods 4. The structure shown in Fig. 4 is substantially like the structure shown in Fig. 3, except that the web members are plates designated 14, having openings 14^a through which the wire bars or rods 4 pass, and in the center of said plates 14 are openings 15, through which the spindle, not shown, is to be inserted.

40 It is obvious from the foregoing, that 45 various changes may be made without departing from the spirit and scope of the invention, and I, therefore, do not wish to be confined to either of the specific forms shown, except as claimed in the appended 50 claims.

What I claim is:—

1. A wire reel including rectangular shaped end members, a plurality of horizontally disposed and parallel arranged rods 55 connecting said end members, said rods having angular ends intersecting the corners of said end members at or adjacent the ends of said rods, and other members connecting said rods adjacent the bends forming said 60 angular ends and forming webs and having openings to receive a spindle or the like.

2. A wire reel including rectangular shaped end members, a plurality of horizontally disposed and parallel arranged rods 65 connecting said end members, said rods hav-

ing angular ends intersecting the corners of said end members and "lap" welded thereto at or adjacent the ends of said rods, and other members connecting said rods adjacent the bends forming said angular ends and 70 forming webs and having openings to receive a spindle or the like.

3. A wire reel including rectangular shaped end members, a plurality of horizontally disposed and parallel arranged rods 75 connecting said end members, said rods having angular ends intersecting the corners of said end members, and other members connecting said rods, each formed of twisted body portions having end loops to receive 80 said rods and central openings to receive a spindle or the like.

4. A wire reel including rectangular shaped end members, a plurality of horizontally disposed and parallel arranged rods 85 connecting said end members, said rods having angular ends intersecting the corners of said end members and "lap" welded thereto, and other members connecting said rods, each formed of twisted body portions having 90 end loops to receive said rods and central openings to receive a spindle or the like.

5. A wire reel including rectangular shaped end members bent into form from a single piece of wire and "butt" welded at 95 their meeting ends, a plurality of horizontally disposed and parallel arranged rods connecting said end members, said rods having angular ends intersecting the corners of said end members at or adjacent the ends of said rods and "lap" welded thereto, and other members connecting said rods adjacent the bends forming said angular ends and 100 forming webs and having openings to receive a spindle or the like.

6. A wire reel including rectangular shaped end members bent into form from a single piece of wire and "butt" welded at 105 their meeting ends, a plurality of horizontally disposed and parallel arranged rods connecting said end members, said rods having angular ends intersecting the corners of said end members and "lap" welded thereto, and other members connecting said rods adjacent the bends forming said angular ends and 110 forming webs and having openings to receive a spindle or the like.

7. A wire reel including rectangular shaped end members, a plurality of horizontally disposed and parallel arranged rods 115 connecting said end members, said rods having angular ends intersecting the corners of said end members, and having depressions where the angular ends and bodies of said rods meet, other members connecting said rods, said connecting members formed of 120 radially disposed arms having loops seated in said depressions, and having axially disposed openings to receive a spindle or the like.

8. A wire reel including end members formed from a single strand of wire bent into proper shape, a plurality of horizontally disposed and parallel arranged rods by being welded thereto, and other members connecting said rods adjacent the bends forming said angular ends and forming 10 webs and having openings to receive a spindle or the like.

5 connecting same end members, said rods having angular ends connected to the end members at or adjacent the ends of said rods

JOHN SOMMER.
